POCKET DOOR PULL

John G. Sterling, Crystal Lake, and Thorwald Ohman, Chicago, Ill., assignors to John Sterling Corporation, a corporation of Illinois

Application June 24, 1955, Serial No. 517,836

2 Claims. (Cl. 16—124)

This invention relates generally to building hardware and more particularly to an improved door pull especially useful with sliding doors.

At present sliding doors employ either edge pulls or flush pulls or both depending on the particular installation. Normally a pocket sliding door, or that is, one which is arranged to recess into a concealed pocket, employs an edge pull for retrieving the door from the pocket. Most edge pulls comprise a lever system, a retractable finger engaging hook or a plate with an opening for the operator's finger whereby the door may be grasped. The use of an edge pull, however, does not afford a finger engaging opening in the side of the door as is normally provided by means of a flush pull. Therefore, pocket door installations, as now known often include both edge and flush pulls. The expense and manufacturing inconvenience of providing both types of pulls makes it desirable to seek another solution to the problem and to that end our present invention is directed.

Particularly vexatious in present flush pull use is the problem of pinching the fingers when the sliding door recesses into its concealing pocket. Edge pulls likewise have their drawbacks, foremost of which is their inability to provide a means for engaging the door at areas other than at the edge. This limitation causes much inconvenience in operating a partially open door, for example, or in bringing the door into engagement with a striker installed in the door jamb for locking the door in its closed condition.

Recognizing the need for an improved product in these circumstances we have set about to devise a new and improved door pull especially useful with sliding doors which embodies a unique construction permitting use of the pull as either an edge pull and/or a flush pull. The exact means by which we accomplish this structural advancement will be recognized more fully from descriptive materials found hereinafter.

Among the objects of our invention is the provision of a new door pull for sliding doors.

Another object of this invention is to provide a new and improved construction for a door pull whereby such is functional as an edge and/or a flush pull in sliding doors and the like.

The above and further objects, features and advantages of this invention will be recognized by those familiar with the art from the detailed description of its features and construction which follows. Such description will be especially understood in view of the illustrated embodiment found in the accompanying drawings.

In the drawings:

Figure 1 is a partial perspective view illustrating a typical pocket door installation embodying the improved pull of our invention;

Figure 2 is an enlarged partial and elevational view displaying the appearance of the operating end of our improved door pull;

Figure 3 is a side elevational view of the pull means

2

shown in Figure 2, illustrating the same in its installed condition with the edge of a door;

Figure 4 is a cross-sectional view taken along line 4—4 of Figure 3; and

Figure 5 is a cross-sectional view taken substantially at 5—5 of Figure 3.

Turning now to Figure 1 of the drawings in particular, it will be recognized that an improved pull 10 of this invention is installed along the leading edge of a sliding door indicated generally by numeral 11; such door being installed in a receptive pocket frame in the particular embodiment illustrated and cooperating to close over a suitable door opening defined by door jamb assembly 12 according to conventional practice. The particular features of the door installation do not pertain to our present invention since such is directed specifically to the improved pull for use with the sliding doors of the pocket variety as illustrated. Without dwelling further therefore on the surroundings and circumstances in which the improved pull of our invention may be employed we will turn now to its structural features and to the elements which comprise the improved combination of this invention.

With regard to Figure 2 of the drawings, note that our improved pull assembly 10 comprises a substantially U-shaped casing made up of two identical halves or shell portions 15 and 16 each of which is formed by suitable casting, stamping or drawing operations from materials such as brass or like metal. Each half member 15 or 16, as the case may be, comprises a front wall 20 and a transversely related side wall portion 21, as seen from Figure 3. The side wall portion 21 is curved, as at 22, to avoid sharp corners and improve its operating safety and general appearance.

The side wall 21 and the front wall 20 are each indented inwardly to present a recessed finger receiving pocket 23. Such pocket is defined substantially by a curvilinear wall section 24 (see Figure 4) extending between wall portion 21 and a raised lip portion 25, which defines one lateral edge of a reduced front wall portion 20a. Note in particular that lip portion 25 and the central wall portion 24 of the pocket recess are inter-defined by a reentrant curved portion 26. The wall portion 24 and the side wall 21 are interjoined by curved portions adjacent their upper and lower ends as at wall portions 27 and 28. Such upper and lower wall portions 27 and 28 are each invaded by openings for the passage of a fastening screw 29, 29. Each of such curved wall portions 27 and 28 also integrally merges with upper and lower wall portions 30 and 31, respectively, which are formed as integral portions of the side wall portion 21 and front wall portion 20.

It will be appreciated that when installing a pull 10 of our invention a single cut-out of substantially rectangular formation is made in one edge of the door as indicated generally by numeral 33. By placing of the two half segments or shells 15 and 16 in registering back-to-back relation whereat their front walls 20 abuttingly engage or overlap along adjacent edges 34 (see Figure 2) such pull is then disposed in suitable position for connection with the door as by fastening the screw means 29. In regard to the fasteners 29 it will be understood that such pass through the upper and lower end walls 27 and 28 of the finger engaging recess or pocket as described hereinabove and invade the door 11 for securely fastening the pull halves in place.

In the particular embodiment illustrated our improved edge pull is shown in association with a standard 1½ inch door. In such an installation the edges 34 of the two pull halves abuttingly engage as described. The positioning of one front wall 20 in front of the corre-

sponding front wall 20a of shell 16, for example, permits a lateral adjustment of the pull to accommodate variations in door thickness. The particular size of the pull, shown in full scale herein, is designed to accommodate doors having thicknesses of from 1 $\frac{1}{8}$ inches to 1 $\frac{3}{4}$ inches. Thus the pull is versatile for covering a range of door thicknesses which substantially embrace the normal thicknesses employed in residential construction.

It will be appreciated additionally that by stamping the two shell halves 15 and 16 in the manner illustrated, the front wall portions 20 and 20a thereof are reduced in lateral dimension sufficiently to provide a clearance portion or necked-down area 35 to accommodate at least a partial passage of the operator's fingers when shutting the door. While such passage or clearance 35 is not sufficient to accommodate the full thickness of the operator's fingers, it is nevertheless sufficient to prevent or substantially eliminate pinching the user's fingers. In addition to its operation as an edge pull, which is brought about by merely grasping the two sides of the pull between forefinger and thumb for advancing or moving the door according to the desired direction of motion, the raised lip 25 permits operation of the pull from the side of the door as a flush pull.

Thus we have set forth the features and characteristics of the improved door pull of our invention and while we appreciate that numerous changes, modifications and substitutions of equivalent materials may be made therein, it is nonetheless thought that such will not necessarily depart from the spirit and scope of the inventive concepts disclosed and involved herein. As a consequence it is not our intention to be limited to the particular embodiment of the invention illustrated in the accompanying drawings and described hereinabove except as may appear in the following appended claims.

We claim:

1. A door pull of the class described for use with sliding doors, comprising, a two part casing having parallel

side wall portions and a pair of front wall portions, one related transversely to each of said side wall portions, said front wall portions being disjointed and arranged for adjacent interengagement in the assembly of the pull over a leading edge of a door, and a finger receiving pocket opening inwardly of the planes of said front and side wall portions in each part of said casing, the arrangement being such as to produce a dimensionally reduced area in the front wall of said casing for permitting the operator to grasp the pull simultaneously inwardly of the planes of said side wall portions and across the thickness of the door.

2. A door pull of the class described for use with sliding doors, comprising, a two part casing comprising two identical half segments each having a side wall portion and a front wall portion related transversely with respect to each other, a recess opening inwardly of the planes of said related side and front wall portions, a raised lip portion defined substantially along the length of the intersection of said front and side wall portions in each recess, and means accessible within each recess for attaching said casing segments in back to back registering relationship at one edge of a door such that the front wall portions of said two casings form an enclosing bridge across the leading edge of the door with the said recesses accessible to the sides and leading edge of the door to afford the user a finger engaging pocket for operating the pull as an edge pull and a flush pull.
